STENCIL PRINTING MACHINE

Warren Childers, Houston, Tex., assignor, by mesne assignments, to American Type Founders Co., Inc., Elizabeth, N. J., a corporation of Delaware

Application July 19, 1955, Serial No. 523,048

15 Claims. (Cl. 101—124)

This invention relates to printing methods and apparatus, and more particularly to a stencil printing machine.

The subject of the present invention is an apparatus which may be attached to a conventional reciprocating bed letter press, and comprises a frame across which is stretched a stencil or silk screen adapted to be moved past a rotary platen while ink is forced through the apertures in the stencil to produce an image upon the paper mounted on the platen. The critical element of this type of device is the squeegee means for forcing ink through the apertures of the stencil. The disadvantage of prior mechanisms have been attributable to the inability to obtain uniformity of pressure along the entire length of the squeegee against the stencil, thereby resulting in the printing of non-uniform impressions.

In order to overcome the defects of prior art machines, I have devised novel means for forcing the ink through the apertures of the stencil, and the salient feature of the invention is the provision of a flexible squeegee in the form of a hollow resilient or elastic tube which may be inflated as circumstances require for producing the requisite uniform pressure against the stencil or silk screen.

The provision for inflating and deflating the squeegee tube also permits the operating edge thereof to be retracted from the surface of the stencil during its return, non-printing pass, thereby reducing frictional wear upon the stencil by substantially fifty percent, and therefore virtually doubling its life.

By reason of the fact that the squeegee tube is inflated, the pressure exerted by the squeegee is uniform along its entire length and consequently ink will be urged uniformly through the entire width of the stencil or silk screen producing a uniform impression upon the printing paper or print receiving fabric. This feature obviates the defects of prior art machines whose mechanically supported squeegees have a tendency to sag in their mid-sections, or which require special and complex mechanical support means.

A pumping system is connected to the inflatable squeegee and a simple valve is provided to differentiate between the pressure branch of the system, on the one hand, and the exhaust or relief branch, on the other hand. The operation of the valve is coordinated with the motion of the stencil carriage reciprocating past the platen of the machine whereby the squeegee tube is inflated during the printing pass of the stencil carriage and deflated or relieved during the non-printing return pass of the carriage. In those embodiments where the squeegee tube is at least partially immersed in ink, the deflating action of the tube is arranged to cause the ink to be transmitted toward the operative edge of the squeegee whereby an immediate supply of ink is ensured at the beginning of the next printing pass of the stencil.

Still other objects and advantages of my invention will be apparent from the specification.

The features of novelty which I believe to be characteristic of my invention are set forth herein and will

2

best be understood, both as to their fundamental principles and as to their particular embodiments, by reference to the specification and accompanying drawings, in which:

Figure 1 is a schematic side elevation, partly in section, some parts being omitted, showing the reciprocating silk screen and its carrier in relation to the printing platen, and the latching and valve mechanism therefor, prior to the printing operation;

Fig. 2 is a view similar to Fig. 1, showing the apparatus in a position subsequent to the printing operation;

Fig. 3 is similar to Figs. 1 and 2, showing the apparatus during the printing operation;

Fig. 4 is a top plan view of the apparatus shown in Figs. 1, 2 and 3, some parts being omitted, some parts broken away and some parts being added;

Fig. 5 is a section view taken on line 5—5 of Fig. 4;

Fig. 6 is a section view taken on line 6—6 of Fig. 4;

Fig. 7 is a greatly enlarged perspective and section view of the ink tray and squeegee shown in Figs. 1 through 4;

Fig. 8 is a view showing a cross section of the squeegee and ink tray shown in Fig. 7 with the squeegee inflated;

Fig. 9 is similar to Fig. 8 and shows the squeegee in the deflated position;

Fig. 10 is a greatly enlarged schematic section view of the valve mechanism shown in Fig. 4, together with a schematic representation of the inflating and deflating pumping system, shown in position for inflating the squeegee;

Fig. 11 shows the valve mechanism of Fig. 10 in position for deflating or relieving the squeegee;

Fig. 12 is a greatly enlarged perspective view of an alternative embodiment of the squeegee;

Fig. 13 is a cross section view of the squeegee shown in Fig. 12 in the inflated printing position;

Fig. 14 is similar to Fig. 13, showing the squeegee in the deflated position, and showing the means for causing ink to flow toward and onto said squeegee; and

Fig. 15 is an elevation of the mechanism shown in Fig. 12 in the direction of the arrow.

Referring now to the drawings, and particularly to Figs. 1, 2 and 3, there is shown a horizontal stationary press bed 21 which is mounted upon the main frame (not shown) of any standard type of printing machine. Slidably movable back and forth over the surface of the press bed 21 is a substantially rectangular carriage 22 which is reciprocated on the press by means (not shown) that are well known in the printing art. The forward end of carriage 22 has an upwardly extending shoulder 23.

Positioned above carriage 22 is any standard type of rotary platen 24 which carries the paper or other print receiving surface and which is adapted to be rotated in the direction of the arrow by suitable mechanisms (not shown) coordinated with the reciprocating motion of carriage 22, said mechanisms being well known in the printing art, therefore obviating the necessity for providing a further description thereof.

Mounted on surface 25 of carriage 22 is a substantially rectangular frame, generally designated 26, said frame being connected to carriage 22 and moving therewith in a reciprocating path. Frame 26 comprises a forward bar 27, a rearward bar 28, and side bars 29 and 30. Frame 26 may be provided with a floor 31 of sheet metal or the like, whereby the frame may, in some embodiments, perform the function of an ink tray. Floor 31 may have upwardly extending flanges 32 extending into suitable grooves in bars 27, 28, 29 and 30 (Figs. 4 and 5) in order to prevent leakage of ink. In other embodiments carriage 22 may be provided with a pair of longitudinal upwardly extending guide rails 35 (Figs. 4 and 5) for stabilizing the reciprocating motion of frame 26.

Stretched over frame 26 is a stencil 36, which may be in the form of a silk screen or the like, the edges of which

are folded downward over the external walls of the frame and secured thereto by means of suitable pins 37, or the like. (See Fig. 4.)

Positioned transversely within frame 26 and below stencil 27 is an elongated inking assembly, generally designated 41, which is movable longitudinally within frame 26, and at times, independently of the motion of said frame. Inking assembly 41 contains the stencilling or printing ink and also supports a squeegee whose upper edge is adapted to force ink through the pores or openings in the stencil onto the paper carried by platen 24. The structural details of the squeegee will be described hereinbelow.

Connected to the rearward portion of ink assembly 41 are a pair of rearwardly extending guide tubes 42 and 43 whose rearward ends extend through the rearward bar 28 of frame 26. The rearward ends of tubes 42 and 43 telescopically accommodate guide rods 44 and 45, respectively, the rearward ends of said rods being rigidly secured by suitable means to the upwardly extending flange 47 of bracket 48 attached to press bed 21.

A transversely positioned slide bar 51 has a pair of apertures which slidably accommodate guide bars 44 and 45, said bar being normally urged forwardly from flange 47 by means of springs 52 coiled around guide bars 44 and 45.

Mounted by welding or otherwise upon guide tubes 42 and 43 are brackets 55 and 56 having upwardly extending arms 57 and 58, respectively. Extending through arms 57 and 58 is a rotatable rod 61 at the ends of which are mounted pivotable latches 62 and 63 adapted to engage and disengage hooks 64 and 65, respectively, attached to slide bar 51. Latches 62 and 63 are normally maintained in engagement with hooks 64 and 65, respectively, by springs 67, shown in Figs. 1, 2, 3 and 4, but omitted from Fig. 6 for the sake of clarity of illustration.

Connected between brackets 55 and 56, on the one hand, and bar 51 on the other, are springs 68 which normally cause the rear ends of guide tubes 42 and 43 to abut bar 51. While springs 68 are shown in Figs. 4 and 6 as being connected to brackets 55 and 56, Figs. 1, 2 and 3 show said springs attached to arms 57 and 58 for the sake of clarity of illustration, the functions in both positions being equivalent.

Since latches 57 and 58 are both mounted fast upon rotatable rod 61, the rotation of one latch causes the corresponding rotation of the other latch. Connected to the upwardly extending arm 71 (Fig. 4) of latch 62 is the laterally extending arm 72 of longitudinal pull rod 73 slidably supported in bracket 74 mounted on the side of press bed 21. The forward end of rod 73 terminates in an inwardly extending hook 75 which is engageable by finger 76 mounted on carriage 22. Upon forward movement of carriage 22, finger 76 engages hook 75 causing rod 73 to move forward in order to rotate latches 62 and 63 which disengage from hooks 64 and 65, respectively, the purpose of this operation being described hereinbelow.

The sequence of the printing cycle is schematically illustrated in Figs. 1, 2 and 3. Fig. 1 shows the apparatus in position at the beginning of the cycle prior to impressing a reproduction of the stencil upon the paper. The paper upon which the design or printing is to be impressed is wrapped around rotary platen 24, and is held thereon in the manner well known in the art. Latches 62 and 63 are locked to hooks 64 and 65, and carriage 22 begins to move forward to the right, as shown in Fig. 3. At the same time springs 52 urge bar 51 to the right thereby causing guide tubes 42 and 43, and accordingly, inking assembly 41, to move to the right. Although carriage 22 and frame 26 continue in their longitudinal motion to the right, inking assembly 41 moves to the right only a limited distance as determined by bar 51 abutting against upwardly extending bracket 78 mounted on press bed 21. The inking assembly 41 is brought to rest by this means at a point where the upper edge of the

squeegee is positioned substantially directly below the vertical diameter of platen 24.

At the time when the squeegee reaches its rest point, the lead edge of the paper on platen 24 is passed downward upon and meets the forward end of stencil 27 which continues its longitudinal motion with frame 26, the ink being forced by the squeegee through the stencil upon the paper which is arranged to move at the same velocity as the stencil. By this means the squeegee is maintained in the optimum printing position for squeezing the ink through the stencil and onto the paper.

After an impression has been printed upon the paper on platen 24 and the latter has passed out of contact with stencil 36, bar 28 of frame 26 comes into engagement with inking assembly 41 and draws the latter and stencil 36 clear of the platen. At the point when the paper has been printed, and just prior to, or simultaneously with, the engagement of bar 28 with inking assembly 41 to draw it to the right, latches 62 and 63 are disengaged from hooks 64 and 65 by means of finger 76 engaging hook 75 of pull rod 73. (See also Fig. 4.)

Tubes 42 and 43 thereupon slide longitudinally to the right over guide rods 44 and 45 against the action of springs 68. During the return transit of carriage 22 to the left, at which time no printing takes place, inking assembly 41 is urged to the left back to its original position as shown in Fig. 1, by the independent action of springs 68, during which time finger 76 has released hook 75 on pull rod 73 permitting springs 67 to cause latches 62 and 63 to engage hooks 64 and 65, respectively, on bar 51. The rear ends of guide tubes 42 and 43, sliding over rods 44 and 45, cause bar 51 to move to the left against the action of springs 52. The machine is now ready to begin another printing cycle.

The inking assembly 41 comprises an elongated container of sheet metal, or the like, having floor 81, front wall 82 and rear wall 83 extending transversely within frame 26. See Figs. 7, 8 and 9. Mounted on the forward face of wall 83 is a bracket 84 made of sheet metal, casing or the like, having a forwardly and upwardly extending guard flange 85 terminating in an obliquely upwardly extending lip 86, said bracket, flange and lip extending longitudinally in respect of said inking assembly. The forward wall 82 of the inking assembly has a downwardly and rearwardly extending shoulder 87 which is terminated by shelf 88 which extends forwardly to the rear face of wall 82.

Positioned within the chamber defined by floor 81, walls 82 and 83, flange 85 and shoulder 87, is an elongated tube 91, made of a resilient and flexible material such as rubber, neoprene, or the like, and having an upwardly and forwardly extending longitudinal tongue in the form of a squeegee 92 which is confined slidably in the mouth formed by lip 86 and shoulder 87.

Tube 91 has a pair of apertures 92 along its rear wall which are matched with a corresponding pair of apertures 93 and wall 83, through which is connected a pair of tubes 94, which communicate with an air supply tube 95, as shown in Fig. 4. In some embodiments, a single air supply tube 95 may communicate directly through wall 83 with the interior of tube 91. Since tube 95 is connected to a pressure and vacuum system, to be described hereinbelow, it is apparent that tube 91 may be inflated or deflated in accordance with the requirement of causing the upper edge of squeegee 92 either to be urged upward against the underside of stencil 36 (Fig. 8), or to be retracted therefrom (Fig. 9).

In the embodiment shown in Figs. 7, 8 and 9, guard 85 and lip 86 are provided for the purpose of limiting the expansion of tube 91 when air or gas is introduced therein under pressure, since the tube may be made of uncorded rubber or similar elastic material. Tube 91 may alternatively be made of corded rubber which would limit its expansion under pressure, in which event guard 85 and lip 86 may be dispensed with.

Mounted on the rear face of wall 83 of inking assembly 41 is an elongated ink duct 97 having a plurality of apertures 98 which register with corresponding apertures 99 and 101 in wall 83 of bracket 84, respectively. Said apertures permit ink from the duct to flow into the ink assembly 41 and over flange 85 which also has a plurality of apertures 102 which permit ink 103 to flow down on to the upper surface of tube 91, particularly when the latter is deflated. (Fig. 9.) Although perforations 102 may be omitted in flange 85, these perforations are desirable in some embodiments in order to wet the upper surface of tube 91 with ink so that a portion thereof may be carried upwards with the squeegee adjacent the inner surface of lip 86. Communicating with the interior of duct 97 is an ink supply tube 108 which extends rearwardly of the machine through bar 28 of frame 26, the rear end of said tube being connected to a flexible hose 109 which leads to an ink supply reservoir, not shown.

The rear end of air supply tube 95, which also extends through bar 28 of frame 26, is connected to one end of flexible hose 111, the other end of which is attached to inlet tube 112 positioned on one side of valve box 113 and communicating with the valve chamber 114 therein. Valve box 113 is shown in plan view in Fig. 4, and in enlarged schematic cross section detail in Figs. 10 and 11.

On another side of valve box 113 are pressure inlet tube 115 and exhaust outlet tube 116 communicating with the valve chamber 114. Inlet pressure tube 115 is connected by suitable means, not shown, to pressure line 117, connected in turn to pressure tank 118. Exhaust outlet tube 116 is connected by suitable means, not shown, to exhaust line 119, connected in turn to exhaust tank 120. Pressure tank 118 and exhaust tank 120 are each connected by way of suitable check valves 123 and 124, respectively, to a pumping mechanism 125 operated by motor 126. Motor 126 is connected to a suitable power source by way of lead lines 127 and 128. Connected in series in lead line 127 is an electric pressure meter 131 whose pressure sensitive element communicates with the interior of tank 118. Meter 131 is adjusted automatically to close or break the circuit in lead line 127 controlling motor 126 in accordance with desired gas pressure within predetermined limits in tank 118. Check valves 123 and 124 serve as limit controls upon the respective pressures in tank 118 and tank 120 in a manner well known in the art.

The alternate inflation and deflation of tube 91 first urges squeegee 92 against stencil 36 during the printing pass of frame 26; and then deflates said tube, retracting the squeegee during the non-printing return pass of the frame. This is accomplished by providing within chamber 114 of valve box 113, a valve block 131 having a pressure passage 132 and an exhaust passage 133 that are spaced apart a lesser amount than the distance between pressure inlet 115 and exhaust outlet 116.

Valve block 131 is movable longitudinally within valve box 113 and when pressure passage 132 registers with pressure inlet 115, exhaust outlet 116 will be shut off by the mass of block 131 (Fig. 10). Alternatively, when exhaust passage 133 registers with exhaust outlet 116, pressure inlet 115 will be shut off in like manner (Fig. 11).

Both passages 132 and 133 communicate with an elongated recess 134 in the upper surface of block 131, which in turn communicates with valve inlet 112 regardless of the position of said block within chamber 114. Thus, the longitudinal movement of block 131 in one direction or the other will provide a differentiation between the pressure portion and the exhaust portion of the pumping system.

Connected to the rearward end of valve block 131 is rod 137 which extends slidably through end cap 138, threadably mounted over the end of valve box 113. Rod 137 extends slidably through support bracket 139

mounted on press bed 21 and is terminated by laterally extending finger 141 which is engaged by bar 51 as the latter moves rearwardly. Connected to the forward end of valve block 113 is rod 143 which extends slidably through the end wall of valve box 113, and extends slidably through a pair of support brackets 144 mounted on press bed 21, and is terminated by laterally extending finger 145 which is engaged by bracket 146 mounted on frame 26.

When carriage 22 has moved to a point just short of its forwardmost position after the printing pass, as shown in Fig. 2, bracket 146 engages finger 145 and causes it to move rod 143 forward, whereby valve block 131 is also moved forward to a point where exhaust line 119 is in circuit with tube 91 of the squeegee mechanism. See Fig. 11. Tube 91 is thereby deflated causing retraction of squeegee 92 from stencil 36 (Fig. 9), at which time carriage 22 begins its return motion to its starting position in Fig. 1.

During the transit of carriage 22 to its starting position, valve block 131 remains in its evacuating position until the carriage reaches a point just short of the starting position, at which time bar 51, moved rearwardly by guide tubes 42 and 43, engages finger 141, which now causes rod 127 to pull valve block 131 into the pressure position as shown in Fig. 10. At this time tube 91 is inflated (Fig. 8), causing squeegee 92 to rise and be urged against screen 36 during the entire printing pass of the machine, as described hereinabove.

The locations of fingers 141 and 145 on rods 137 and 143, respectively, relative to bar 51 and bracket 146, respectively, are arranged to provide an alternation of the valving mechanism between the pressure condition and evacuating condition for operating squeegee 92 in synchronized timing with the pass of stencil 36 past platen 24 during the printing and non-printing portions of the cycling action of the machine. Fingers 141 and 145 may be adjusted on rods 137 and 143, respectively, in different positions thereon for accommodating the alternation of the pressure-exhaust system with stencils 36 and/or frames 26 of varying sizes which might require different timing cycles on the part of the inking mechanism.

It will be noted that normally there is a slight clearance between the periphery of the paper mounted on platen 24 and stencil 36 on frame 26 whereby the plane of the stencil is ordinarily spaced apart from the periphery of platen 24 and of the paper wrapped around it. In previous mechanisms, various mechanical arrangements are required to urge the stencil 36 against the paper on platen 24 by means of an inking roller or squeegee, said arrangements being subject to mechanical failure as well as manifesting lack of uniformity of impression across the whole width of the paper to be printed.

In the apparatus of the present invention, however, mechanical expedients for lifting the squeegee to urge the stencil against the platen have been completely eliminated, and there has been substituted the extremely simple inflatable squeegee which has no mechanical parts to get out of order, and which provides a uniform pressure along the whole width of the stencil to impress sharply defined reproductions upon the paper on platen 24. During the return pass of the stencil when no printing takes place, the simple deflation of the squeegee permits the stencil to bypass the platen without the danger of accidental transfer of ink to the platen.

An alternative embodiment for an inking and squeegee mechanism is shown schematically in Figs. 12, 13, 14 and 15. In this embodiment, the whole frame 26 serves as a reservoir containing the ink, and the squeegee assembly, which extends laterally within said frame, is movable longitudinally therein by suitable means, not shown, which are comparable to the means shown in Figs. 1 through 4.

In this alternative embodiment, there is a platform 151 mounted on a plurality of rails 152 which slide longi-

tudinally on floor 31 of frame 26. Mounted by means of hinges 153 to platform 151 are a plurality of ramps 154 which extend downwardly into the pool of ink 155. Mounted by suitable means on platform 151 is a flexible squeegee tube 156 having a plurality of longitudinal ridges 157 (Figs. 12, 13 and 14). Communicating with the interior of tube 156 is an air supply tube 158, comparable in function to tube 95 (Fig. 4), and connected by suitable means not shown, to valve box 113.

Tube 156 may be inflated (Fig. 13), in the manner described hereinabove, causing ridges 157 to be urged upwards against the underside of stencil 36, or it may be deflated (Fig. 14), thereby retracting the ridges from the stencil. While the squeegee assembly moves in a direction opposite to floor 31 during a portion of the non-printing transit thereof, ink is caused to rise on ramps 154 and to flow onto the ridges 157 of deflated tube 156, as shown in Fig. 14.

In this manner, the ridges are provided, during the non-printing pass of the machine, with a supply of ink which is retained in said ridges until the printing pass of the machine is instituted, as in Fig. 3, and squeegee is inflated. Here again, as in the previous embodiment, a uniform pressure is maintained along the whole length of the squeegee, thereby providing a sharp definition of the printing impression along the whole width of the print.

In the embodiment shown in Figs. 12 through 15, ink is supplied to the ink reservoir on floor 31 of frame 26 by way of an ink duct 161 having one or more outlet apertures 162. Ink duct 161 is supported by a bracket 163 which is attached by means, not shown, to a suitable portion of the machine. Ink duct 161 has a supply tube 164 which leads to an ink reservoir (not shown). The feeding of ink to duct 161 as well as to ink duct 97 (Figs. 1, 2, 3) may be provided by suitable pressure of gravity means as the circumstances require.

It will be understood that where a squeegee tube 156 of the type in Fig. 12 is used, it is preferably made of a corded rubber or the like, which would prevent any excessive expansion of the tube. It is apparent that the ridged squeegee tube 156 may be substituted for tube 91 and squeegee 92 in the embodiment shown in Fig. 7.

In some embodiments, squeegee tubes 91 and 156 may be made of a material the structure and constitution of which cause it to maintain the operative edge of the squeegee normally retracted from stencil 36, in which case it is unnecessary to provide for an exhaust branch in the pumping system. In these circumstances, only a pressure pumping system need be utilized, with a suitable relief valve 167 (Fig. 4), well known in the art, being inserted into pressure line 95 for permitting the squeegee tube to retract when the pressure circuit is closed by valve block 131 during the return pass of carriage 22.

In the specification, I have explained the principles of my invention, and the best mode in which I have contemplated applying those principles, so as to distinguish my invention from other inventions; and I have particularly pointed out and distinctly claimed the part, mode or combination which I claim as my invention or discovery.

While I have shown and described certain preferred embodiments of my invention, it will be understood that modifications and changes may be made without departing from the function and scope thereof, as will be clear to those skilled in the art.

I claim:

1. A stencil printing machine comprising means for forcing ink through the stencil and being in the form of a tube of flexible material, a longitudinal portion of said tube being in the form of a squeegee, means for inflating the tube to cause the squeegee to be urged against the stencil when said squeegee moves in one direction relative to said stencil, and means for relieving pressure within the tube to cause the squeegee to be retracted com-

pletely from the stencil when said squeegee moves in the opposite direction relative to said stencil.

2. A stencil printing machine according to claim 1, and further comprising a stencil, a carriage upon which said stencil is mounted, means for producing reciprocating motion upon said carriage, and means on said carriage for operating the inflating and relieving means in timed relation to the motion of said carriage.

3. A stencil printing machine comprising means for forcing ink through the stencil and being in the form of a tube of flexible material, a longitudinal portion of said tube being in the form of a squeegee, a plurality of longitudinal ridges on the squeegee portion of the tube, means for inflating the tube to cause the ridges to be urged against the stencil when said squeegee moves in one direction relative to said stencil, and means for deflating said tube to cause the ridges to be retracted completely from the stencil when said squeegee moves in the opposite direction relative to said stencil, said ridges being adapted to be supplied with ink when said tube is deflated.

4. A stencil printing machine according to claim 3 wherein said tube is composed of corded resilient material, the cordage therein being adapted to limit the expansion of the tube.

5. A stencil printing machine comprising a carriage adapted for reciprocating motion, an inking assembly mounted transversely on said carriage and movable longitudinally therein and independently of portions of the motion of said carriage, means for maintaining said inking assembly motionless during a portion of the motion of said carriage during the printing operation, a stencil mounted on said carriage over said inking assembly, a squeegee in said inking assembly, said squeegee having the form of a flexible tube, means for inflating said tube to urge a longitudinal surface portion thereof against the stencil when said portion moves in one direction relative to said stencil and means for deflating said tube in order to retract said portion completely from said stencil when said portion moves in the opposite direction relative to said stencil.

6. Apparatus according to claim 5 wherein the carriage has a forward transit and a return transit, the printing operation taking place only during the forward transit, and further comprising means for inflating the tube during the forward transit of said carriage, and means for deflating said tube during the return transit of said carriage.

7. A stencil printing machine comprising a carriage adapted for reciprocating motion, a stencil mounted on said carriage, a rotary platen mounted transversely above said carriage, said stencil being normally spaced apart slightly from the periphery of said platen, an inking assembly mounted transversely on said carriage underneath said stencil and movable longitudinally therein, a squeegee on said inking assembly, said squeegee having the form of a flexible tube, means for inflating said tube whereby said squeegee causes the stencil to be urged against the rotating platen during the printing pass of said carriage, and means for deflating said tube in order to retract said squeegee and to permit the stencil to resume its spaced apart condition from the platen during the return pass of the carriage.

8. A machine according to claim 7, and further comprising means for moving the squeegee independently of the motion of said carriage, and means for maintaining said squeegee motionless during the printing pass of the carriage.

9. A machine according to claim 7 wherein said tube is made of corded rubber whereby the expansion of said tube is limited.

10. A machine according to claim 7, and further comprising means mounted on said inking assembly adjacent said tube and adapted to limit the expansion thereof.

11. In a stencil printing machine having a carriage adapted for reciprocating motion and a stencil on said

carriage, an inking mechanism comprising a frame positioned transversely of said carriage and movable longitudinally therein on one side of said stencil, a flexible tube mounted longitudinally in said frame, a longitudinal squeegee mounted on said tube, means for inflating said tube to urge said squeegee against the stencil when said squeegee moves in one direction relative to said stencil, and means for deflating said tube for retracting said squeegee from said stencil when said squeegee moves in the opposite direction relative to said stencil.

12. A machine according to claim 11, and further comprising a guard longitudinally mounted in said frame adjacent said tube and adapted to limit the expansion thereof.

13. A machine according to claim 11, and further comprising a flange on said frame forming a mouth therewith through which said squeegee protrudes, said mouth being adapted to guide the movement of said squeegee between its printing position and its retracted position.

14. A machine according to claim 11, and further comprising a flange connected within said frame extending

over a portion of said tube to limit the expansion thereof, and a plurality of apertures in said flange for permitting ink to flow onto the squeegee.

15. A stencil printing machine comprising a carriage adapted for reciprocating longitudinal motion, a stencil mounted on said carriage, a flexible tube mounted transversely in said carriage and movable longitudinally relative to said stencil and said carriage, a squeegee edge on said tube normally retracted from said stencil, means connected to said tube and adapted to inflate the tube to cause the squeegee to be urged against said stencil as the latter moves past said squeegee in one direction, and means relieving the pressure in said tube to permit said squeegee to be retracted from said stencil during the opposite motion of said stencil.
